BLENDER

Ralph Morris, St. Paul, Minn., assignor to Fingerhut Manufacturing Co., Minneapolis, Minn., a corporation of Minnesota

Filed Jan. 22, 1968, Ser. No. 10,254

Term of patent 14 years

Int. Cl. D7—05

U.S. Cl. D89—1

FIG. 1 is a perspective view of a blender, showing my new design;

FIG. 2 is a right side elevational view;

FIG. 3 is a front elevational view;

FIG. 4 is a rear elevational view;

FIG. 5 is a top plan view; and

FIG. 6 is a bottom plan view.

A power cord is shown fragmentarily for convenience of illustration.

I claim:

The ornamental design for a blender, as shown and described.
